UNITED STATES PATENT OFFICE.

MARCELLUS H. PITTS AND ISRAEL R. WHITEMAN, OF MARSEILLES, ILLINOIS.

WIRE-BARBING MACHINE.

SPECIFICATION forming part of Letters Patent No. 313,103, dated March 3, 1885.

Application filed October 13, 1884. (No model.)

To all whom it may concern:

Be it known that we, MARCELLUS H. PITTS and ISRAEL R. WHITEMAN, citizens of the United States of America, residing at Mar- 5 seilles, in the county of La Salle and State of Illinois, have invented certain new and useful Improvements in Wire-Barbing Machines, of which the following is a specification, reference being had therein to the accompanying 10 drawings.

Figure 1 is a top plan view. Fig. 2 is a side elevation. Fig. 3 is a cross-sectional view of the machine on line 1 of Fig. 1, showing a side view of the barb-wire-feeding mechanism. 15 Figs. 4 and 5 are perspective views of the barbing-wire friction-blocks. Fig. 6 is a central longitudinal section of the strand-wire-crossing mechanism. Fig. 7 is a cross-sectional view of the machine on line 2 of Fig. 20 1, showing a side view of the mechanism by means of which a pair of toothed racks are reciprocated to oscillate the hooked fingers to weave the barb in between the twists of the strand-wires. Fig. 8 is a face view of the 25 gearing of the strand-wire-crossing mechanism. Fig. 9 is a face view of the pawl and ratchet and their immediate connecting parts of the strand-wire-crossing mechanism, showing a cross-section of the head to which the 30 pawl attaches, and which incloses the ratchet-wheel. Fig. 10 is a perspective view of the head, which contains the barb-wire cutters, and also the hooked fingers for weaving the 35 barbs between the twists of the strand-wires and their oscillating mechanism, and also shows said cutters and hooked fingers, and the racks and pinions for oscillating said fingers. Fig. 11 is a perspective view of a portion of the central part of said last-described 40 head, showing guide-blocks for holding the barbs in proper position so they will be caught by the hooked fingers when said fingers oscillate. Fig. 12 is a side view of the outer end of the cut-off lever, showing its form and the 45 form of the cam which operates it to cut off a barb. Fig. 13 is a cross-section of the head which holds the cutting-punch, to show the manner in which it is held in said head. Fig. 14 is a plan view showing and locating 50 the strand-wires, the barb, the hooked fingers, and the cutters, to show their relative posi-

tions, the dotted lines showing different positions of the strand-wires and of the barb and of the hooked fingers as the barb is being woven between the twists of the strand-wires; 55 and Fig. 15, a perspective view of a section of barbed wire such as is made by this machine, forming a two-strand two-pointed wire barb.

This invention relates to certain improvements in wire-barbing machines of that class 60 which attaches a two-pointed wire barb to two twisted strand-wires by weaving the barb between the twists of the strands in such manner that the body of the barb will pass between the twists of the strand-wires between 65 three separate consecutive twists or crosses of the strands, leaving two prods to project from opposite sides of the strand-wires in opposite directions from each other, the barb when completed being somewhat of the shape of the letter **S** interwoven between or in three consecutive twists of the two strand-wires. 70

Referring to the drawings, A represents the bed of the machine, mounted on suitable legs, A', and to which the parts are attached for 75 supplying the strand-wires with barbs, and for taking up the strand-wires after they have been barbed, so they may enter the twister and be spooled.

Power is applied by a belt over pulley D of 80 the twister-yoke.

At one side of pulley D, and keyed to the twister-yoke, is a spur-gear, G, which drives spur-wheel G² of shaft B through the medium of an idler spur-gear, G', studded to bed A, 85 and also drives spur-gear G³ of shaft S through the medium of said gears G' and G². The shaft B is supported a little above and near one side of bed A in suitable boxes, and has rigidly secured on its inner end a circular 90 head, P³, which rotates continuously with it close to the back of an annular gear, P. The side of head P³ next the annular gear P is hollowed for the reception of a ratchet-wheel, P², which is integral with and projects from 95 the back of annular gear P. Within, attached to, and near the periphery of head P³ is a spring-pawl, P¹, having a rear extending arm arranged to project through an opening in head P³ when engaged with the ratchet-wheel 100 P². This combined integral gear P and ratchet-wheel P² are sleeved on a short core-shaft,

B', in such manner as to bear against the side of spur-gear P', which is keyed to said core-shaft at or about its center. When core-shaft B' has thus been provided with the parts described, its rear end is passed into hollow shaft B of the circular flanged head P³ in such manner that ratchet-wheel P² will be next to and within the flange of head P³, so that spring-pawl P⁴ will engage with the teeth of ratchet-wheel P², as shown in Fig. 6. (See also Figs. 8 and 9.) The shaft B is hollow and receives one end of and forms a bearing for said core-shaft B' to rotate in.

To core shaft B', and within the annular gear P, is keyed a spur-gear, P', having only one-half the number of teeth as gear P, and driven by annular gear P through the medium of the intermediate idler-pinions, P⁵ and P⁶. (Shown in Figs. 6 and 8.)

To the outer extending end of core-shaft B' is attached by suitable cap-screws a plate, B³, having projecting from its face a pair of curved tubes which connect with openings extending through the length of core-shaft B', and through which tubes and openings the strand-wires are threaded. These tubes are shown in Fig. 6, and curve slightly toward each other. The idler-pinions P⁵ and P⁶ are studded to and properly supported by standard P⁹, (shown in Figs. 1 and 2,) which standard is also formed to support the outer extending end of core-shaft B'. The circular rotating head P³ is partially surrounded by a pair of curved arms, P⁷ and P⁸, (shown in Fig. 9,) and are for the purpose of engaging with the rear extending-arm of pawl P⁴, to hold it disengaged from the ratchet-wheel P² one-half the time—one-eighth at one side and three-eighths at the other—so that as the head P³ rotates continuously the annular gear P will be rotated intermittently and only one-half the time; but when the annular gear P does rotate it rotates the spur-gear P' and core-shaft B' at twice the speed as shaft B and head P³ by means of the intermediate pinions, P⁵ and P⁶, as the annular gear P has twice the number of teeth as spur-gear P'. A pair of wooden friction-ports, F F, held by long bolts against the sides of annular gear P, serve as a brake to prevent said gear from rotating only when compelled to by the engagement of pawl P⁴ with ratchet-wheel P².

To the outer end or side of spur-gear G² is attached a strand-wire spool-yoke, R, arranged to hold two spools of plain strand-wire, and is adapted to rotate with said gear and shaft B. The strand-wires are fed from these spools through hollow shaft B and through the openings in core-shaft B', emerging from the curved tubes B², and from thence pass to head H, where they are supplied with barbs, and thence between a plate and compress-roll and over a take-up wheel to the twister and spooler.

The head H, where the barbs are attached to the strand-wires, is constructed in two parts—an upper and a lower part—each part having

portions H' and H² of its front hinged thereto, so said front portions H' and H² may be opened to get at the working parts within the head, which are nearly covered by them when closed. (See Fig. 10.) The lower part of head H holds the cutting-off die d', and the upper part of said head holds the sliding head H³, which in turn holds the cutting-off punch d by means of the wedge-shaped block d² and screws d³. (See Figs. 10 and 13.)

Within and near one end of the hinged portions H' and H² of head H are a pair of short shafts, having heads X and X' on their facing ends and pinions J and J' near their central parts, which pinions project from said hinged portions of head H into channels formed therein, as shown in Fig. 10. The toothed racks D⁵ and D⁶ are placed in channels in the side of head H in such manner as to engage with the pinions J and J' when the parts H' and H² are closed to head H, and as said racks are reciprocated they will in turn operate the hooked fingers Z and Z'. These racks D⁵ and D⁶ are held in their respective channels by plates n and n', secured to head H, and respectively to the hinged portions H' and H², which serves to hold said hinged portions clasped to head H as well as to hold in the racks. Other screws are also used to properly hold the parts H' and H² to head H.

Fig. 11 shows guide-plates Z², Z³, Z⁴, and Z⁵ as they would appear placed between the upper and lower parts of head H when the hinged portions H' and H² are closed. The upper part of head H is broken away in said figure to more clearly show said parts. The strand-wires emerge from the ends of the tubes B² and pass over the upper surface of guide-plate Z², under guide-plate Z³, and on to the take-up. The barb b is fed in from the back of head H through guide-tube Y at right angles with the two strand-wires and emerges from between the guide-plates Z³ and Z⁴ in their crotch, and out over plate Z², and between the two strand-wires, (see Figs. 10, 11, and 14,) and under finger t, which is shown in Figs. 1 and 2, which finger covers plate Z² and forms an upper guide for the barb in connection with plate Z². When the part H' of head H is closed to head H, the oscillating head X' stands immediately over guide-plate Z⁴, and in such position that the hooked barbing-finger Z', attached to it, will oscillate between the two plates Z³ Z⁴. When the part H² of head H is closed to head H, the oscillating head X, having the barbing-finger Z attached to it, stands immediately under plate Z², and in such position that said finger may oscillate between said plate and finger t above it.

After the barb-wire is thus fed in between the two strand-wires, the core-shaft B', having the tubes B², from which the strand-wires emerge, rotates one-half way around, to cross the strand-wires in front of the barb, as shown in Fig. 14, and the punch d then descends just far enough to hold the barbing-wire be-

tween it and the die d' below while the barb is being interwoven between the three several twists of the two strand-wires, but not cut it loose until the barb has undergone such process and becomes thoroughly attached. The two strand-wires having thus been crossed the first time, the hooked barbing-finger Z then oscillates forward, catches the outer extending loose end of the barb in the hollow on its end, and carries it forward and bends it around into the crotch of the cross of the strand-wires, as shown by the dotted lines 1 in Fig. 14. Core-shaft B^2 again rotates one-half way around to cross the strand-wires 15 again forward of the barb just bent into their last cross, as shown by the dotted lines in said figure. The hooked barbing-finger Z' then oscillates and catches the outer extending end of the barb-prod and carries it forward from its position shown by dotted lines 1 in said figure to the position shown by dotted lines 2, to lie in the crotch of the cross thus formed in the strand-wires, thus weaving the barb in between the three consecutive twists or crosses 20 of the strand-wires to form the finished barbed strand-wires. (Shown in Fig. 15.) After the portion of the barbing-wire forming the barb has thus been attached to the strand-wires, the punch d descends a little farther to shear 25 the barb loose in a diagonal manner from the barbing-wire, so that the strand-wires may be drawn along by the take-up far enough for the next succeeding barb to be placed on in like manner.

30 While a barb is being applied to the strand-wires it is necessary that they should be held firmly and in a fixed position immediately back of the place where the barb is to be so attached, so the proper twists or crosses may 35 be thus given to them, and prevent the twists from extending any farther beyond than to the place where they are so held. This is accomplished by means of a punch, S^6 , (shown in Figs. 1 and 2,) which is operated to be 40 driven forward to press against the two strand-wires immediately back of the place where the barb is to be applied, and in between the guides Z^2 and Z^3 , holding them firmly against the head H while the barb is being applied to 45 the strand-wires.

50 The mechanism that operates the punch S^6 is constructed in such manner that it will withdraw said punch from contact with the strand-wires immediately after each barb is thus attached to permit the strand-wires with the barb attached, to be drawn forward by the take-up, so the next succeeding barb can be attached. This punch S^6 is arranged to be 55 thus reciprocated in the head S^7 , which attaches to the lower part of the part H^2 of head H , and is caused to so reciprocate by means of the channeled cam S^8 on shaft S , Fig. 1, through the medium of lever S^9 and link S^5 , the said lever being pivoted to the outer end 60 of arm S^4 , and having a friction-roller to travel in the channel of cam S^2 . This cam is so set

on shaft S that it will cause punch S^6 to press on the strand-wires only while the barb is thus being interwoven in the twists of the strand-wires, and then recede so they may be 70 drawn on through the machine, as stated.

The mechanism for reciprocating the toothed racks D^3 and D^6 , as stated, to oscillate the hooked barbing-fingers and the shafts and heads to which they are attached, is shown in 75 Fig. 7, and consists of a pair of bars, $D^1 D^2$, attached to said racks at their inner ends, and arranged to slide in recesses in standard A^2 at their outer ends. Bar D^2 , which connects with rack D^6 , has a depending arm to engage with 80 the cam D^4 , and bar D^1 has an upturned extending arm to engage with the cam D^3 . These cams are each keyed on shaft S , and when rotated will, by means of their engagement with said arms, reciprocate the racks D^3 and D^6 in 85 one direction, but in opposite directions from each other, to oscillate the hooked barbing-fingers to weave a barb between the twists of the strand-wires, as stated. A pair of springs, arranged to draw on the bars D^1 and D^2 , reciprocate said racks in the other direction to 90 return the two hooked barbing-fingers to their initial position to manipulate the next succeeding barb, as stated.

The mechanism for feeding in the barbing-wire b is shown in Fig. 3, and consists of a reciprocating head, c , having a pair of rollers, $c^1 c^2$, over which the barb-wire travels, and a pair of depending spring-dogs, $c^3 c^4$, immediately over said rollers, between which and 95 said rollers the barb-wire b passes. The reciprocating head c rests in proper guideways, E , secured to the back of head H , and is caused to reciprocate by means of cam S' , keyed on shaft S , and a coil-spring connecting the outer end of lever c^5 with the bed of the machine or the floor below through the medium of said pivoted lever c^5 , having the upturned arm c^6 and pitman c^7 , as shown in said figure. When cam S' rotates, it will, through the 100 medium of rocking lever c^5 , oscillate arm c^6 , and, by means of the pitman connecting said arm with said head, reciprocate it. When it moves forward, the barb-wire b will be grasped by the spring-dogs $c^3 c^4$ between them and the 105 rollers $c^1 c^2$, and fed forward far enough to furnish wire enough for a barb. When said head moves backward, the wire b remains stationary as the dogs $c^3 c^4$, stand, so they release their grip and slide on it backward ready for 110 a new grip on the wire when the head c moves forward again. The barbing-wire is thus fed into the machine from the rear of head H , as before stated, through an opening in it, in an intermittent manner as needed, and at the 115 right time to deliver enough for a barb. A pair of grooved friction-blocks, $c^8 c^9$, such as are shown in Figs. 4 and 5, are arranged on the post c^5 , Figs. 1 and 3, and are given tension by means of a set-screw through the head of 120 post c^5 , through the medium of spring-cushion c^{10} , Fig. 3. These friction-blocks $c^8 c^9$ are

arranged so the grooves in their faces will meet and so the wire will lie in said grooves, and are for the purpose of holding the wire in its place and for straightening it as it is drawn or fed through between them. The stroke of the head c is regulated by means of the set-screw c^{10} in the outer end of arm c' , Fig. 3.

The lever H^4 , which operates the cutting-off punch d , is fulcrumed between a pair of ear-lugs on the upper end of head H . The front and shortest end of said lever passes through a mortise in the upper end of sliding head H^3 , which holds the said punch, while its rear end extends out over shaft S . (See Figs. 1, 7, 10, and 12.) The part of said lever H^4 which is directly over shaft S has attached to its under side the depending lug H^5 , as shown particularly in Fig. 12, to engage with and ride on cam H^6 , keyed on shaft S , which cam is of the proper form to raise that end of said lever to cause the cutting-off punch d to descend, as stated. The coil-spring shown in Fig. 12 will return said lever and punch after a barb has been severed from the barbing-wire. When the strand-wires have thus been barbed, they pass out of the barbing part of the machine, first over the drag-wheel T and on farther to a twister and spooler, T^2 , as stated, as shown in Fig. 2, and they are drawn through the machine intermittently, so the barbs may be attached to them while they are still, and so the barbs may be placed on at equal distances apart from each other. This is accomplished by means of the waved cam R^3 , keyed on shaft S , and the pawl and ratchet mechanism shown in Figs. 1 and 2. The ratchet-wheel R' of this mechanism is keyed on shaft K , as is also drag-wheel T , the shaft K being boxed to bed A , as shown in said figures. On shaft K , and at the side of ratchet-wheel R' , is fulcrumed an oscillating lever, R^2 , which has a spring-pawl attached to its lower end to engage with the ratchet-teeth on the periphery of ratchet-wheel R' , and a pair of friction-rollers, r , studded to its upper end, between which the waved periphery of cam R^3 rotates. When said cam rotates, it will, by means of such connection, oscillate lever R^2 , which will, by means of its spring-pawl engaging with the ratchet-teeth of wheel R' , impart an intermittent forward rotary motion to the drag-wheel T , to intermittently take up the barbed strand-wires from the machine, as and for the purpose stated. The periphery of drag-wheel T is provided with a series of equidistant chambers for the reception of a series of removable lugs, V^2 , having V -shaped ends, in which the strand-wires lie in passing over said wheel, as shown in Figs. 1 and 2. These lugs V^2 are removable, so they may be replaced when worn, and they furnish more certain means of drawing the strand-wires out of the machine by reason of the said lugs catching behind the barbs. As the barbed strand-wires pass from the head H , where they are barbed, to said

drag-wheel, they pass between a grooved plate, V' , and a compressor-roll, V , (shown in Figs. 1 and 2,) which plate and roll are supported on the bed A in the frame V^3 . Tension is given to the roll V by means of a pair of set-screws, m' , and rubber cushion m , which bear against the sliding boxes of said roll. The plate V' is grooved so the strand-wires will be pulled along in said grooves and under said roll for the purpose of causing said roll to press the strand-wires down into said groove in such manner as to bend the prods of the barbs laterally slightly, so they may not drop out from between the strand-wires. Hollow shaft B is provided with an opening in its side, as shown in Fig. 2, for convenience in threading the strand-wires through it. An eyelet, b' , attaches to the standard A^2 and serves as a guide for the barbing-wire, so it may properly enter the feed, as shown in Fig. 1. When the drag-wheel T draws out a certain quantity of finished barbed wire, it is immediately taken up by that part of the machine commonly called the "spooler and twister," which forms no part of this invention, as almost any of the ordinary spoolers and twisters will perform the service required in this machine. The finished product of this machine is shown in Fig. 15.

Having thus described our invention, what we claim as new, and desire to secure by Letters Patent, is as follows, to wit:

1. In the wire-barbing machine described, the mechanism, substantially as shown and described, for supporting and intermittently twisting the strand-wires, consisting of the head P , spring-pawl P^1 , annular gear P , core-shaft B' , having the extending tubes B^2 , spur-gear P' , and intermediate idler-pinions, $P^5 P^6$, as and for the purpose set forth. 105

2. In the wire-barbing machine described, the mechanism, substantially as shown and described, for holding and cutting off the barbs from the barbing-wire, consisting of the die d' , punch d , lever H^4 , and cam H^6 , arranged as set forth. 110

3. In the wire-barbing machine described, the mechanism, substantially as shown and described, for feeding the barbing wire in the machine and between the cutting-dies and strand-wires, consisting of the reciprocating head c , having the spring-dogs c^2 , and grip-rolls c' , pitman c^6 , lever c^7 , having the up-turned arm c^8 , and cam S' , in combination with the grooved friction-blocks $c^9 c^8$, spring and cushion c^4 , supported on post c^3 , as and for the purpose set forth. 115

4. In the wire-barbing machine described, the means, substantially as shown and described, for intermittently taking up the strand-wires after they have been barbed, consisting of the wheel T , having the inserted forked lugs V^2 , ratchet-wheel R' , cam R^3 , and lever R^2 , having a spring-pawl to engage with ratchet-wheel R' , and a pair of friction-rollers, $r r$, to engage cam R^3 , in combination with the means for compressing the barb and strand 120 125 130

wires, and for bending one of the barb-prods, consisting of the roller V and plate V', substantially as set forth.

5. In the wire-barbing machine described, the means, substantially as shown and described, for intermittently twisting the strand-wires by rotating them one-half way around each time in the same direction, consisting of the head B³, spring-pawl P⁴, annular gear P, 10 core-shaft B', having the extending tubes B², spur-gear P', and intermediate idler-pinions, P⁵ P⁶, whereby the barbs may be interwoven between each of three consecutive twists of the strand-wires, in combination with the 15 hooked barbing-fingers Z Z' and their operating mechanism, as set forth.

6. In the wire-barbing machine described, the means, substantially as shown and described, for holding the strand-wires in a 20 fixed position within their guides in head H while they are being supplied with barbs, consisting of the punch S⁶, connecting-link S⁵, lever S³, and cam S², arranged to operate in the manner specified.

25 7. In the wire-barbing machine described, the mechanism, substantially as shown and described, for feeding the barbing wire in the machine and between the cutting-dies and strand-wires, consisting of the reciprocating head c, having the spring-dogs c², and grip-rolls c', pitman c⁶, lever c⁷, having the up-turned arm c⁸, and cam S', arranged as set forth.

8. In the wire-barbing machine described, 35 the hooked barbing-fingers Z Z', in combination with the oscillating heads X X' and their shafts, and pinions J J' and racks D⁵ D⁶, and

their operating mechanism, arranged as and for the purpose set forth.

9. In a wire-barbing machine, the combination of the hooked barbing-fingers Z and Z', to weave the barbs between consecutive twists of a pair of strand-wires, means, substantially as shown and described, for oscillating them, and the means for intermittently crossing the strand-wires and holding them in a fixed position while the barbs are being applied, as set forth. 40 45

10. In the wire-barbing machine described, the head H, having the hinged portions H' H', 50 and arranged to support the cutting-off dies d d', racks D⁵ D⁶, pinions J J', oscillating heads X X', having the hooked fingers Z Z', and the guides Z² Z³ Z⁴ Z⁵, in the manner and for the purpose set forth. 55

11. In the wire-barbing machine described, the combination of the stationary head H, having the die d', and parts H' H², sliding head H³, having the punch d, wedge-block d², and screws d³ for securing said punch to said 60 sliding head, barbing-fingers Z and Z', and the means, substantially as shown and described, for operating said punch and die and barbing-fingers, as and for the purpose set forth. 60

12. In a feeding mechanism for wire-barbing machines, the combination of the rollers c' c', spring-dogs c² c², and reciprocating head c and their operating mechanism, as set forth. 65
